UNITED STATES PATENT OFFICE.

LOUIS G. MASSICOTTE, OF PROVIDENCE, RHODE ISLAND, AND GEORGE C. BOSWELL, OF DANIELSON, CONNECTICUT, ASSIGNEES TO M-B TOOL COMPANY, OF PROVIDENCE, RHODE ISLAND, A CORPORATION OF RHODE ISLAND.

VALVE-GRINDER.

1,244,526.

Specification of Letters Patent. Patented Oct. 30, 1917.

Application filed April 26, 1916, Serial No. 93,784. Renewed June 11, 1917. Serial No. 174,163.

To all whom it may concern:

Be it known that we, LOUIS G. MASSICOTTE and GEORGE C. BOSWELL, citizens of the United States, said MASSICOTTE residing at 5 Providence, county of Providence, State of Rhode Island, said BOSWELL residing at Danielson, county of Windham, and State of Connecticut, have invented a new and useful Valve-Grinder, of which the following is 10 a specification.

This invention relates to a tool for use in grinding valves of automobiles.

The principal objects of the invention are to provide a simple and convenient tool 15 for this purpose which can be converted from an ordinary screw-driver to a valve grinder of that type in which two prongs separated from each other are arranged to engage in slots in the valve to be ground; 20 also to provide a construction in which the distance apart of these prongs can be regulated readily, and especially to provide an arrangement whereby the members carrying these prongs can be moved back out of the 25 way, without danger of dislodging them from the shank, so as to expose the screw-driver sufficiently to permit it to be used in the ordinary way.

Reference is to be had to the accompanying drawings in which—

Figure 1 is an elevation of a tool constructed in accordance with this invention, showing the parts in the position for grinding a valve;

Fig. 2 is an edge view showing the parts in the position shown in Fig. 1;

Fig. 3 is a view similar to Fig. 1 showing the parts drawn back so as to expose the screw-driver sufficiently for that to be 40 used, and

Fig. 4 is a side view of one of the jaws.

The tool is shown as comprising a single piece shank A having an offset a, and a handle B at the end to facilitate rotation 45 of the shank which is provided with a flattened end C constituting a screw-driver. The shank is provided with a pin c projecting from opposite sides thereof constituting pivots for a pair of jaw members D. These 50 jaw members are provided with longitudinal slots d for the pins. They are also provided each of them with a prong d' and with a transverse slot d'.

Through a longitudinal slot a' in the

screw - driver passes a bolt E having a 55 thumb nut F thereon for securing it in position. This bolt passes through the transverse slots d' of the two prong members, and it will be obvious that they can be adjusted out and in and clamped in adjusted 60 positions by this screw.

When it is desired to use the device as an ordinary screw-driver either for valve grinding or for any other purpose the thumb nut and bolt are loosened and the two jaws 65 are moved straight back toward the handle, the slots being provided for permitting this motion to take place without disengaging the jaws or the bolt from the shank. This position of the parts is shown in Fig. 3. 70 It will be noted that the prongs lie along the shank when retracted so as not to project outwardly and be in the way.

This is an improvement over the devices known in the market for the reason that the 75 two implements constitute a unitary device which can be used for both purposes without danger of becoming disengaged. Therefore the losing of the jaws is prevented, and at the same time the adjustment is quick and 80 easy and sufficiently accurate for the purposes intended. Furthermore the members D are held in position when drawn back as shown in Fig. 3 by tightening up the nut. In this way there are no parts likely to be 85 lost and no complications introduced into the operation of valve grinding by the use of this tool. On the contrary that operation is greatly facilitated and yet the tool can be manufactured and sold at a very small price. 90

Although we have illustrated and described only a single form of the invention we are aware of the fact that modifications can be made therein by any person skilled in the art without departing from the scope 95 of the invention as expressed in the claims. Therefore we do not wish to be limited to all the details of construction herein shown and described, but what we do claim is:—

1. As an article of manufacture, a tool 100 for grinding valves and the like comprising a handle portion, a shank having an offset intermediate portion and a screw - driver form at the end of the shank, a pair of members mounted on opposite sides of the screw - driver form and adjustable toward and from each other, and means for holding 105 said members in adjusted positions, each of

said members being provided with a projecting prong.

2. As an article of manufacture, a tool for grinding valves having a shank provided with a screw-driver shaped end, two members located on opposite sides of said end and adapted to be adjusted toward and from each other, each member having a prong at the end adapted to extend beyond the end of the screw-driver, and means whereby said members can be drawn back on the end of the shank without disengaging them therefrom and clamped in their retracted position.
- 15 3. As an article of manufacture, a valve grinder comprising a shank provided with a pair of offset members thereon, each having a longitudinal slot at one end, and a transverse slot, each having a projection extending materially beyond said transverse slot, and means for securing said members to the shank through the transverse slots, said shank having means for entering the longitudinal slots.
- 20 4. As an article of manufacture a valve grinder having a screw-driver shank, a pronged member thereon, and means for clamping said pronged member in two positions, in one of which the pronged member projects beyond the end of the screw-driver and in the other of which it does not.
- 25 5. As an article of manufacture, a valve grinder comprising a shank having a double pin thereon and a bolt and nut, and

a pair of pronged members on opposite sides 35 of said shank each having a longitudinal slot for receiving said stud, and a transverse slot for receiving said bolt, said shank having a longitudinal slot along which the bolt can be adjusted.

40 6. As an article of manufacture, a tool of the character described comprising a shank having a longitudinal slot therethrough, a fastening device adjustable along said slot, and two jaw members adjustable therewith.

45 7. As an article of manufacture, a tool of the character described comprising a shank having a longitudinal slot therethrough, a fastening device adjustable along said slot, 50 two jaw members adjustable therewith, and means on the shank for guiding said jaw members.

8. As an article of manufacture, a tool of the character described comprising a shank 55 having a longitudinal slot therethrough, a fastening device adjustable along said slot, and two pronged valve grinding members adjustable with said fastening device to project the prongs of said members when they 60 are advanced, and to move them back to a position along the shank when they are retracted.

In testimony whereof we have hereunto set our hands.

LOUIS G. MASSICOTTE.
GEORGE C. BOSWELL.
